No. 37,271.

Patented December 20, 1904.

UNITED STATES PATENT OFFICE.

HARRY FRANKEL, OF NEW YORK, N. Y.

DESIGN FOR A HAT-REST.

SPECIFICATION forming part of Design No. 37,271, dated December 20, 1904.

Application filed August 11, 1904. Serial No. 220,427. Term of patent 7 years.

To all whom it may concern:

Be it known that I, HARRY FRANKEL, a citizen of the United States, residing at New York city, county and State of New York, have invented a new, original, and ornamental Design 5 for a Hat-Rest, of which the following is a specification.

The drawing is a perspective view of a hat-rest of my new, original, and ornamental design.

What I claim is—

The ornamental design for a hat-rest as shown.

HARRY FRANKEL.
